UNITED STATES PATENT OFFICE.

LOUIS COHEN, OF WASHINGTON, DISTRICT OF COLUMBIA.

METHOD OF WIRELESS SIGNALING.

1,220,072.

Specification of Letters Patent. Patented Mar. 20, 1917.

Application filed November 13, 1915. Serial No. 61,332.

To all whom it may concern:

Be it known that I, LOUIS COHEN, a citizen of the United States, residing at Washington, in the District of Columbia, have 5 invented certain new and useful Improvements in Methods of Wireless Signaling, of which the following is a specification.

This invention relates to a new and improved method of interrupting the current 10 in a high frequency oscillatory circuit for wireless signaling purposes, and is particularly applicable to the arc-system of wireless signaling.

The present invention has for its primary object an important and practical improvement in the method of radio signaling by the arc system. The method now generally used in signaling by the arc system consists in the use of the so-called compensation wave method. In that method there is current flowing in the antenna circuit and energy radiated all the time, but the wave length is changed in signaling, that is, for dots and dashes energy is radiated at a definite wave length, say six thousand meters, for instance, and for the spaces between dots and dashes energy is radiated at a slightly different wave length, say fifty-eight hundred meters. The objection to this compensation wave method is that the energy is radiated all the time, and at two different frequencies for two different intervals, which is at times confusing to the operator. Furthermore, when a number of stations are in operation, and each station is radiating energy at two different frequencies, the trouble from interference is greatly increased.

In contradistinction to the compensation wave method referred to, the present invention provides novel and practical means whereby signaling by the arc system can be accomplished by using one wave length only. That is, according to the present invention, energy will be radiated on dots and dashes, but no radiation of energy at all occurs on spaces. In other words, the present invention provides a means whereby the current flow in the antenna circuit may be placed under such control that it can be varied from zero to maximum, without introducing any appreciable sparking, and without affecting the operation of the arc.

The preferable embodiment of the inven-

tion of this application is shown in the accompanying drawing, in which—

The figure is a diagram of a wireless signaling system containing the invention.

The essential features of the improved method of radio signaling by the arc system may readily be explained in connection with the diagram shown in the drawings, wherein the numeral 1 is an antenna, 2 and 2^a inductance coils, 3 an arc excited from the usual direct current source g, 4, 4^a, 4^b ground connections, 5, 5^a fixed condensers, 6, 6^a electrodes, 7 an electrolytic solution, 8 a container, 9, 9^a leads, and 10 an electrode operating device of any suitable mechanical or electrical type. The operation is as follows:

When the two electrodes 6 and 6^a are brought close together, two complete circuits are formed to which the arc can supply energy; one is a loop circuit consisting of 75 arc 3, lead 9, inductance coil 2^a, condenser 5^a, lead 9^a which connects to electrodes 6, 6^a and grounds 4^b, 4. The other is the antenna circuit consisting of antenna 1, inductance coil 2, lead 9, arc 3, and ground 4. Since 80 the loop circuit is of smaller resistance than the antenna circuit for the reason that it is a closed circuit and there is no radiation, and also because the inductance may be made relatively small, nearly all the current will flow in the loop circuit, and very little, if any, current will pass into the antenna circuit. In fact, by a suitable adjustment of the inductance 2^a and capacity 5^a of the loop circuit, a condition can be 85 realized of having absolutely no current in the antenna circuit when the electrodes 6 and 6^a are brought close together. When the electrodes 6 and 6^a are separated, a resistance is gradually introduced into the 90 loop circuit which reduces the current in that circuit to a very small fraction, 1% or less, and all the energy from the arc is taken up by the antenna circuit, a large current flowing in antenna circuit. The operation is, of course, obvious; by operating the movable electrode 6, the oscillatory current from the arc can be made to flow either in the loop circuit or antenna circuit depending whether the electrodes are close together 95 or separated from each other. In this way, the current in the antenna circuit can be interrupted without breaking the circuit.

For wireless signaling, the actual operation would be to separate the electrodes 6, and 6^a for the dots and dashes, and to bring them together for the spaces between the dots and dashes. The fixed condenser 5 serves the purpose in this case of keeping the arc more steady. In the arrangement described here, an electrolytic resistance is shown to be used in the loop circuit. This is preferable, but not necessary for the operation of the invention, any suitable varying resistance will serve the purpose.

To understand the principle involved in this invention it is necessary to refer briefly to the applicant's theory of the oscillatory arc phenomena which is as follows: In starting the operation of an arc system the arc electrodes (2) are brought into contact thus completing the self-electrical circuit (7). The direct current flowing in the circuit produced by the generator (8) stores up a large amount of electromagnetic energy in the inductance coils which is of considerable magnitude. When the electrodes are separated (25) at the generator side of the arc circuit (3) is opened, electrical energy stored in the inductance coils is given into the oscillatory circuit by charging the condenser (5) converting the electromagnetic energy into electrostatic energy. When the condenser, which in a radio system may be the antenna, is charged to sufficiently high potential to cause a discharge across the gap between the electrodes (30) an arc is formed closing again the generator circuit (8), and the generator again storing up electromagnetic energy in the inductance coil of the direct current circuit at the same time the condenser discharges itself through the completed circuit (4, 2, 9, 40, 3, 1). When the condenser potential has dropped below a certain value depending on the strength of the magnetic blow-out used, the electrodes, etc., the arc is opened again, the cycle of operation outlined above repeating itself.

If we have two oscillatory circuits shunted across the arc, as in the case shown in the figure of the drawings 1, 2, 9, 1, constituting one circuit and 4^b, 6, 6^a, 9^b, 5^b, 2^b, 9, 4 the other, we would expect that when both circuits are closed at the same time electrical oscillations would be generated simultaneously in both circuits. This however is not always the case. The applicant has found (55) that by relatively adjusting the electrical constants of the said two circuits a condition can be obtained where there is an oscillatory current in one circuit which may be termed the absorption circuit (4^b, 6, 6^a, 9^b, 5^b, 2^b, 9, 4) and no current at all in antenna circuit (1, 2, 9, 1). In the light of the above theory of the arc phenomena this can be explained in the following manner:

1. The charging of the condensers 5 and 5^a of the two circuits when the arc is opened re-

quires a certain length of time which may be relatively large or small depending on the time constant of the oscillatory circuit, that is, on the ratio of its inductance to its resistance. Now, as is preferably the case, if we make the condenser 5^a of the absorption circuit larger than the condenser or antenna 5 of the antenna circuit, and at the same time make the time constant of the absorption circuit smaller than the time constant of the antenna circuit, then a condition can be obtained where the potential of the condenser in the circuit whose time constant is small has reached the break-down potential of the arc before the condenser in the other circuit is charged to any appreciable degree. That is to say, in the functioning of my system the electrical time constant of the absorption circuit is smaller than that of the antenna circuit. Since the arc is opened, due perhaps to the magnetic blow-out, before the potential drops to zero value, the result will be that the condenser in the second circuit retains its small charge. The net result is that we have charging and discharging of the condenser in one circuit producing a current flow in it and no current flow in the other circuit. By way of explanation of why it is preferable to have the condenser of one circuit of larger capacity than the condenser of the other circuit, it will be observed that in the circuit of smaller time constant the resistance is less, only a very small inductance being used in that circuit, and for the same energy absorption the current must be made larger, and therefore it is desirable and preferable to have a larger condenser for the absorption circuit than for the antenna circuit.

In the figure we have, as already noted, two oscillatory circuits shunted across the arc. When the electrodes 6, 6^a and the absorption circuit are brought together this circuit is completed, and if its time constant is made small then a large oscillatory current may be developed in it, while there is no current flow in the antenna circuit. If however, the electrodes are opened, a large resistance is thus introduced into the absorption circuit, and the current distribution is accordingly altered, that is, we have a current flow in the antenna circuit and no current in the absorption circuit. Therefore, closing and opening the electrodes (6, 6^a) we can check or start the current flow in the antenna circuit which can be utilized for signaling purposes.

I claim:

- An arc system comprising two oscillatory circuits shunted across the arc, and means for producing radically different electrical time constants in the said two circuits, and to so proportion the said time constants in relation to each other that when both circuits are closed a considerable oscillatory current is produced during the time interval between the opening and closing of the electrodes.

current will exist in one circuit and substantially none in the other circuit.

2. An arc system for radio signaling comprising an antenna circuit and an absorption circuit both in parallel and shunted across the arc, and means for adjusting the electrical time constants of the two circuits in relation to each other so that when both circuits are closed simultaneously and the arc is in operation, there is an oscillatory current flow in the absorption circuit and substantially no current flow in the antenna circuit.

3. An arc system for radio signaling comprising an antenna circuit and an absorption circuit both in parallel and shunted across the arc, and means for varying the resistance of the absorption circuit to thereby vary its

electrical time constant, and thus vary the amount of current flow in the antenna circuit.

4. An arc system for radio signaling comprising an antenna circuit and an absorption circuit in parallel with it, and an electrolytic means of varying the resistance of the absorption circuit to thereby vary its electrical time constant and thus vary the amount of current flow in the antenna circuit.

In testimony whereof I hereunto affix my signature in the presence of two witnesses.

LOUIS COHEN.
